UNITED STATES PATENT OFFICE.

ALEXANDER RUTAN, OF BLACKINGTON, MASSACHUSETTS.

CLAMP FOR DENTAL FLASKS.

1,201,876.

Specification of Letters Patent.

Patented Oct. 17, 1916.

Application filed February 3, 1916. Serial No. 75,970.

To all whom it may concern:

Be it known that I, ALEXANDER RUTAN, a citizen of the United States, residing at Blackington, in the county of Berkshire and 5 State of Massachusetts, have invented certain new and useful Improvements in Clamps for Dental Flasks, of which the following is a specification.

This invention relates to improvements in 10 clamps for securing together the parts of dental flasks during the process of packing dentures and in the subsequent process of vulcanization.

The invention is designed to combine the 15 function of the ordinary rigid press employed for packing rubber gum around the denture within the flask while the gum is being softened for the purpose, and also the function of the ordinary spring clamp 20 press employed to secure the parts of the flask together during the process of vulcanizing the rubber for setting the dentures.

In my prior U. S. application Serial No. 855,971, relating to clamps for dental flasks, 25 I have shown an adjustable spring clamp constructed of non-flakable material and adapted to maintain the requisite compression upon the flasks during the process of vulcanizing.

30 My present invention relates to improved adjusting and tightening facilities adapted to a clamp constructed substantially in accordance with my prior invention. These improvements enable the device to be employed as a clamp in the packing process, so called, as well as in the vulcanizing process, and obviate the usual necessity of providing separate and distinct types of clamps.

Having referred to the general character 40 and purpose of my invention, I will proceed to describe a specific useful form of embodiment thereof, illustrated in the accompanying drawings, wherein—

Figure 1 is a side view of my device 45 showing a pair of dental flasks operatively mounted therein, the relative position of the clamp adjusting means when thrown out of position for compression being shown in dotted lines; Fig. 2, a top view 50 of the same; Fig. 3, a rear view of the clamp, the lower portion being cut away; Fig. 4, a vertical longitudinal section of the clamp in the form and position shown in Fig. 1; Fig. 5, a vertical longitudinal section similar to Fig. 4 shewing a modified form of

clamping adjustment, the forward end of the rocking arm and the lower portion of the clamping device being cut away; Fig. 6, a side view of a modified form of clamp base and upright portion, and Figs. 7 and 60 8, edge and back views, respectively, of a detachable lever for operating the adjusting mechanism.

As shown, in its preferred form, the device is a unitary structure constructed preferably of non-flakable material, such as phosphor-bronze, which is not injuriously affected by gases generated in the vulcanizing process, and comprises a base 1, rounded in outline and having even top and bottom 70 faces, an upright portion 2 secured to the base, and clamping means provided at the upper end of the upright portion. While I have shown the upright portion 2 forming an integral attachment to the base 1, it is 75 apparent that these parts may be separate units and detachably secured together, as illustrated in my said prior application.

The clamping means includes a horizontally arranged rocker arm 3 pivotally mounted upon a shaft 7 journaled at its opposite ends in bearing blocks 8, 8, secured in spaced relation on the front face of the upright portion 2 by screws 9, 9. The rocker arm 3 is arranged to tilt at its forward end toward the base 1, said forward end being provided with a threaded bore to receive a vertically arranged adjusting screw 4 having an enlarged polyhedral head, and supporting at its lower end a presser block 5 movably secured thereto. Said presser block 5 has a flat lower face and is provided on its upper face forwardly with a circular recess 10 to receive the lower end of the adjusting screw 4, which revolves freely therein, downward displacement of the presser block 5 being prevented by a horizontally arranged pin 13 carried by the presser block and projecting through the recess 10, said pin being adapted to take into an annular 100 groove 14 provided at the lower end of the adjusting screw 4. The presser block 5 is prevented from rotating with the adjusting screw 4 by means of a vertically arranged fixed pin 11 seated in a corresponding recess provided in the top face of the presser block in the rear of the adjusting screw and extending upward freely through a transverse bore 12 provided through the rocker arm 3. The upright portion 2 is prefer-

105 110 115

ably crowned lengthwise to decentralize and distribute the stress applied thereto when the clamp is under heavy pressure, and is inclined forward at an angle to the base to 5 center the presser block 5 in its position over the base 1, and the flasks 25, 25, when mounted in superimposed position thereon. The upright portion 2 should be constructed of the metal above mentioned, or of other 10 suitable material, possessing the requisite degree of firmness and resiliency to yieldingly oppose the heavy pressure applied thereto and to resume its original position when the pressure is relieved. These properties may, however, be further insured by 15 the provision of a core 22 of spring steel, as shown in the modification illustrated in Fig. 6, said core being embedded lengthwise in the upright portion 23 and extended 20 downward preferably into the base 24.

The tilting of the rocker arm 3 is accomplished by means of a cam member 15 carried centrally on a horizontally arranged cam shaft 6 secured at opposite ends in 25 spaced blocks 16, 16, provided at the upper end of the upright portion 2 on the rear face thereof and secured thereto in detachable relation by means of screws 17, 17. The cam member 15 is secured in fixed relation upon 30 the shaft 6 and is adapted to be swung upward to engage with and elevate the rear end of the rocker arm 3, which projects through a longitudinal slot 18 provided centrally in the upper end of the upright portion 35 2, the rotation of the cam shaft 6 being accomplished preferably by means of a detachable lever 19 having a transverse opening 20 through one end adapted to receive the extension provided on one end of the 40 shaft 6, the tip 21 of the shaft being preferably squared to conform to the opening 20 of the lever.

In the modification of the adjusting mechanism shown in Fig. 5, the rear end of 45 the rocker arm 30 is provided with a longitudinal slot 31 in which a roller 32 is mounted upon a pin 33 secured at opposite ends in the rocker arm, said roller 32 being arranged to contact with the cam member 50 15, when swung upward to tilt the rocker arm 30, thus reducing the friction of these parts during engagement.

In operation the adjusting mechanism is 55 tilted upward as shown in the dotted lines of Fig. 1 to allow the flasks, 25, 25, to be arranged in superimposed relation on the base of the clamps. The adjusting mechanism is then restored to its original position in which the rocker arm 30 assumes a horizontal position. The presser block 5 is then lowered into engagement with the dental flasks by means of the rotation of adjusting screw 4. Sufficient pressure upon the flasks for the packing process is accomplished by 60 65 means of the adjusting screw without the

additional pressure provided by the tilting of the rocker arm through the medium of the cam 15, and may be varied from time to time as the packing process progresses by the rotation of the adjusting screw 4. During the process of vulcanization, however, when excessive pressure is required the presser block 5 is forced down as far as possible by means of the adjusting screw 4, which is provided with a polyhedral head 70 to enable the operator to apply a hand wrench. When the presser block 5 has been screwed down as far as the flasks will admit, further pressure is produced by tilting the rocker arm downward at its forward end 75 through the medium of the cam 15, the additional tension thereby exerted causing the upright portion of the clamp to yield in its normal position without injuring the flasks. As the process of vulcanization advances 80 and the contents of the flasks are increased or diminished the necessary pressure thereon is maintained by the yielding qualities of the resilient upright portion, thus obviating 85 constant attention and readjusting by the operator.

I claim:

1. In a device of the class described, a base, a resilient upright member secured to the base, a horizontally arranged arm pivoted on the upright member and projecting over the base, and means for tilting the forward end of the pivotal arm toward the 95 base.

2. In a device of the class described, a 100 base, a resilient upright member secured to the base and having a horizontally arranged extension projecting over the base, an adjustable clamping member secured to the forward end of said extension, and means 105 for moving the clamping member toward and away from the base.

3. In a device of the class described, a base, an upright member secured to the base, and clamping means carried on the upright 110 member and including a horizontally arranged arm pivoted to move vertically, means for tilting the pivotal arm toward the base, an adjustable extension member depending from the forward end of the pivotal arm, and means for actuating said extension member toward and away from the 115 pivotal arm.

4. In a dental clamp, a base, an upright portion secured to the base, a horizontally 120 arranged arm pivoted to move vertically on the upright portion and projecting over the base, a clamping member carried on the outer end of said pivotal arm and extending toward the base, means for adjusting 125 the clamping member toward and away from the base, and separate means for tilting said pivotal arm toward the base.

5. In a dental clamp, the combination, with a support including a base and an up- 130

right member secured to the base, of clamping means carried on said upright member and including a horizontally arranged arm pivoted to move toward and away from the base, a cam member for tilting the forward end of said pivotal arm toward the base, an extension member depending from the forward end of said pivotal arm, an adjusting screw for elevating and lowering the exten-

sion member, and means for preventing the extension member from rotating.

In testimony whereof I hereto affix my signature in presence of two witnesses.

ALEXANDER RUTAN.
